UNITED STATES PATENT OFFICE.

PATRICK VINCENT DWYER, OF ST. PAUL, MINNESOTA.

FLUSH-TANK VALVE.

SPECIFICATION forming part of Letters Patent No. 399,506, dated March 12, 1889.

Application filed September 1, 1888. Serial No. 284,335. (No model.)

To all whom it may concern:

Be it known that I, PATRICK VINCENT DWYER, a citizen of the United States, residing at St. Paul, in the county of Ramsey 5 and State of Minnesota, have invented certain new and useful Improvements in Flush-Tank Valves, of which the following is a specification.

My invention relates to flushing-tanks for water-closets, and has reference more particularly to that class in which the valve tips to permit the discharge of water from the tank.

In the drawings, Figure 1 is a vertical sectional view of a portion of a tank, showing the 15 valve closed; Fig. 2, a similar view with the valve opened; Fig. 3, a sectional view of the overflow-tube or siphon on the line xx of Fig. 1; Fig. 4, a top plan view of the valve-seat, and Fig. 5 a perspective sectional view of the 20 same.

A indicates a tank, which may be made of any suitable material and of any desired size and form, said tank being provided with an opening in its bottom, through which passes a 25 tube, B, as shown in Figs. 1 and 2. This tube B is connected with the discharge-pipe by means of a coupling, C, in the ordinary manner, and is provided at its upper end, within the tank, with a laterally-extending flange, B', 30 which rests upon the bottom of the tank, and which is drawn so firmly against the latter by the coupling C as to prevent leakage. In the upper face of the flange B' is an annular groove, a, which will preferably be undercut, 35 as represented in Figs. 1, 2, and 5, to receive and hold a packing-ring, b, which is adapted to form the valve-seat. The exact form of the groove a is a matter that is capable of variation; but it should be such as to hold the 40 packing-ring b firmly in place after the latter has been forced or pressed into the groove without the aid of other devices. The tube or pipe B is further provided with ears d d, to which is pivoted the valve D, the lower edge 45 of the valve resting upon the packing-ring b, so that when closed, as shown in Fig. 1, no water can escape through the tube B. The valve is open at its center, while extending upward from the valve, in line with the opening, is a tube, E, the upper end of which terminates at about the high-water line of the 50 tank.

F indicates a tube of larger diameter than the tube E, which surrounds and is set away from the latter, as shown in Figs. 1 and 2. 55 The upper end of tube F is closed, while its lower end is open to permit the water to pass upward between the tubes E and F and over and into the top of tube E.

The tube F is rendered adjustable upon or 60 with reference to the tube E in any suitable manner, but preferably by means of set-screws G, (shown in Fig. 1,) for a purpose presently explained.

The cap or top of tube F is connected, by 65 means of a rod, H, with an elbow-lever, I, which is pivoted to the tank, while the other arm of the elbow-lever is provided with a rod, chain, or cord, J, extending to any convenient point, as shown in Figs. 1 and 2. When the 70 valve is closed, as in Fig. 1, the water will stand on a level with the upper end of the tube E, the latter acting as an overflow-pipe for the tank. When it is desired to flush the bowl, (not shown,) it is only necessary 75 to pull down upon the chain or cord, and thereby tip the valve D and raise it off its seat, as shown in Fig. 2, the water, of course, flowing as long as the valve is held open. The proper way to do is to tip the valve D, 80 hold it open a moment, and then allow it to resume or return it to its normal position. The opening or tipping of the valve will, of course, destroy the equilibrium of the air-pressure within the tube E and the discharge- 85 pipe; but when the valve is closed to its seat the outgoing or receding water within the discharge-pipe creates a partial vacuum within the tube E. This action, together with the pressure of the air on the surface of the wa- 90 ter in the tank, causes the water to rise up into the space between the tubes E F and flow into the tube E, the tubes or pipes E F acting after the manner of a siphon. The water will continue to flow into the tube E 95 until it falls to the level of the lower edge of the tube F, when the air entering between the tubes E F restores the equilibrium. The tank may now again be filled, the water rising to the top of the tube E.

The amount of water to be siphoned from the tank into the bowl is a matter that can be regulated and controlled as desired by raising or lowering the tube F upon or with 100

reference to the tube E, for the siphoning action is stopped as soon as the water in the tank falls below the lower edge of the tube F.

By means of the set-screws G the tube F 5 may be held in any of its adjusted positions and the siphoning action controlled, as above stated. If this siphoning action is not desired, the outer tube, F, may be omitted and the rod H connected directly with tube E, 10 and in such case water would be discharged only when the valve is tipped and held open or when it overflows into the top of tube E.

By connecting the valve with a rod, as shown, I can actuate it positively in both 15 opening and closing, which is important, in that I am enabled to hold it open and allow the water to run out through the discharge-pipe, or else to close the valve and cause the siphoning to take place.

20 The closing of the valve is not dependent upon the rise of water within the tank, but is effected manually through the connections H, I, and J. This rod H may be of any desired length and extend from the tube E in 25 any direction, thereby enabling the tank to be set up in places where ordinarily it could not be advantageously set up.

20 The principal advantages of the tipping valve are that it cannot be lifted off its seat 30 and may be actuated with considerably less effort than the vertically-moving valves.

An advantage of the construction of the tube B and its packing-ring lies in the fact that the ring can be renewed from time to time without removing or dismounting any other part, and, furthermore, is not liable to be torn, as is the case where it is clamped between two surfaces screwed together. It can be made separately and sold to the trade, if desired, so as to be used with valves differing 35 slightly from that shown herein.

Having thus described my invention, what I claim is—

1. In combination with a flushing-tank, A, having an outlet, a hinged valve, D, provided with an upright tube, E, a shorter tube, F, closed at its upper end and surrounding and separated from tube E, and means for tipping the valve and its tubes positively.

2. In combination with a tank having an outlet, a valve, D, provided with a tube, E, and adapted to close the outlet, and an adjustable pipe, F, closed at its upper end and secured to the pipe E, substantially as and for the purpose set forth.

In testimony whereof I have hereunto set my hand in the presence of two subscribing witnesses.

PATRICK VINCENT DWYER.
